(57) **CLAIM**

The ornamental design for a housing for spill cleanup equipment, as shown and described.

DESCRIPTION

FIG. 1 is a front elevation view of the housing for spill cleanup equipment showing my new design.

FIG. 2 is a right side elevation view of the housing for spill cleanup equipment design.

FIG. 3 is a top plan view of the housing for spill cleanup equipment design.

FIG. 4 is a bottom view of the housing for spill cleanup equipment design.

FIG. 5 is a rear elevation view of the housing for spill cleanup equipment design.

FIG. 6 is a left elevation view of the housing for spill cleanup equipment design.

FIG. 7 is a perspective view showing the left, front, and top of the housing for spill cleanup equipment design.

FIG. 8 is a perspective view showing the right, front, and top of the housing for spill cleanup equipment design.

FIG. 9 is a perspective view showing the left, front, and bottom of the housing for spill cleanup equipment design.

FIG. 10 is a perspective view showing the front, bottom, and right of the housing for spill cleanup equipment design.

FIG. 11 is a perspective view showing the rear, top, and right of the housing for spill cleanup equipment design.

FIG. 12 is a perspective view showing the rear, top, and left of the housing for spill cleanup equipment design.

FIG. 13 is a perspective view showing the rear, bottom, and right of the housing for spill cleanup equipment design; and,

FIG. 14 is a perspective view showing the rear, bottom, and left of the housing for spill cleanup equipment design.
